UNITED STATES PATENT OFFICE.

ADAM ROSS, OF WAUKEGAN, ILLINOIS.

GARMENT.

1,414,155.

Specification of Letters Patent. Patented Apr. 25, 1922.

Application filed May 7, 1921. Serial No. 467,664.

To all whom it may concern:

Be it known that I, ADAM ROSS, a citizen of the Republic of Lithuania, (but who has heretofore applied for first papers to become 5 a citizen of the United States,) residing at Waukegan, in the county of Lake and State of Illinois, have invented certain new and useful Improvements in Garments, of which the following is a description.

10 My invention relates to improvements in garments, and more particularly to that type of garments known as overalls. One of the objects of my invention is to provide a bifurcated garment as above described, which 15 may be worn on either side, that is, the garment is reversible. Another object of my invention is to provide such a reversible overall in which the fly portion may be fastened effectively when the garment is worn 20 on either side. The invention has among its other objects the production of a garment of the kind described which is simple, convenient, durable, and satisfactory for use wherever found applicable. Many other 25 objects and advantages of the construction herein shown and described will be obvious to those skilled in the art from the disclosure herein given.

To this end my invention consists in the 30 novel construction, arrangement and combination of parts herein shown and described, and more particularly pointed out in the claims.

In the drawings, wherein like reference 35 characters indicate like or corresponding parts;

Figure 1 is a plan view of my improved garment;

Figure 2 is a detail of the fly portion 40 thereof, showing the overlying flaps of the fly separated; and

Figure 3 is a sectional view taken substantially on the line 3—3 of Figure 1.

In the drawings wherein I have illustrated 45 a preferred embodiment of my invention, 1 designates the leg or bifurcated portions of my garment, 2 the body portion thereof, 3 the bib and 4 the straps or suspenders for the same. These parts may be of any suitable or preferred form and material. Pockets 5 may be affixed to the garment on either or both sides of the material, in any desired location and of any preferred shape.

At the upper end of the leg portions 1, I

have provided a fly 6, said fly being preferably stitched down, as shown at 7, for a portion of its length. The flaps 8 and 9 of the fly are adapted to overlie one another, as shown in Figure 1, the material of each of the flaps being extended in opposite directions. The outer edges 10 of the flaps are provided with fastening means such as buttonholes, clasps, or equivalent means for the purpose, 11 and 12, said fastening means 11 and 12 being adapted to interengage with 65 buttons or other suitable cooperating fastening means 13 and 14, positioned inwardly of the edges of the flaps 8 and 9 respectively. The buttons 13 and 14 are on opposite faces or sides of the material so that the flap 8 70 will overlie the flap 9, the buttons and buttonholes 12 and 14 cooperating to hold the flap closed in one adjustment of the garment, and the flap 9 will overlie the flap 8 so that the button and buttonholes 11 and 13 may 75 cooperate to close the fly when the garment is reversed. In either of the reversals of the garment, the fastening means at the inner of the free edges of the flaps 8 or 9, as the case may be, are permitted to be free 80 of interengagement. As shown in Figure 2, the eyelets or buttonholes 11 and 12 may be reinforced by a strip 15, this strip serving as a blind if so desired.

Having thus described my invention it is 85 obvious that various immaterial modifications may be made in the same without departing from the spirit of my invention; hence I do not wish to be understood as limiting myself to the exact form, arrangement, construction and combination of parts herein shown and described, or uses mentioned.

What I claim as new and desire to secure by Letters Patent is:

1. A reversible bifurcated garment adapted to be turned inside out and worn on either side, said garment having leg and body portions and a fly therebetween extending upwardly from the crotch and terminating at 100 a point thereabove on the front side only of the garment, said fly comprising overlapped portions and a plurality of pairs of independent fastening means for fastening said flaps in either of the two positions, one 105 of said pairs of means being adapted to be used and one of said pairs being out of use, alternately for each reversal of the garment.

2. A reversible bifurcated garment of the kind described having leg and body portions, and an overlapped fly therebetween, fastening means adjacent the free edge and also inwardly thereof on each of the flaps of said fly, the second mentioned means on one flap being adapted to be free of interengagement with the cooperating means on the other flap in one position of wear, and the second mentioned fastening means of the other flap being adapted to be free of inter-

engagement with the adjacent cooperating means on the other flap when the garment is reversed.

In testimony whereof, I have hereunto 15 signed my name in the presence of two subscribing witnesses.

ADAM ROSS.
